UNITED STATES PATENT OFFICE.

FRANCIS E. RUSSELL, OF HOFFMAN, MONTANA, ASSIGNOR OF ONE-HALF TO
T. H. GARDINER, OF HOFFMAN, MONTANA.

TUG-BUCKLE.

SPECIFICATION forming part of Letters Patent No. 723,317, dated March 24, 1903.

Application filed June 24, 1902. Serial No. 113,035. (No model.)

To all whom it may concern:

Be it known that I, FRANCIS E. RUSSELL, a citizen of the United States, residing at Hoffman, in the county of Park and State of Montana, have invented certain new and useful Improvements in Tug-Buckles; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in tug-buckles, and especially to improvement upon the tug-buckle covered by allowed application, Serial No. 92,833; and it consists in the provision of means for securely locking the hinged lid over the end of a trace securely held to the casing of the buckle.

The invention consists in various details of construction and combinations of parts, as will be hereinafter fully described and then specifically defined in the appended claims.

The invention is illustrated in the accompanying drawings, in which—

Figure 1 is a perspective view of my improved buckle and fastening device. Fig. 2 is a cross-sectional view through the hinged lid. Fig. 3 is an enlarged detail in perspective of the locking-pin; and Fig. 4 is an enlarged view of the hinged plate, showing the slot in which the locking-pin is disposed.

Reference now being had to the details of the drawings by letter, A designates the casing of the buckle, which has longitudinal flanged edges A', from which project in opposite directions the loops C, to which straps are connected which are adapted to pass about the body of an animal. Mounted in the forward end of the flanges is a bolt D, to which a strap is secured, and hinged to one of said longitudinal flanges is a plate F, centrally apertured to receive a pin E, projecting at right angles from the base of the casing. On the outer face of the plate F is a projecting lug or widened portion F', which has a central aperture to receive the end of said pin E, and at right angles to said aper-

ture is a second aperture H, which is formed transversely through said lug and adapted to receive a locking-pin K. Said pin is provided with a head K', which is notched at k 55 in order to provide means for the reception of the nail of a finger of an operator, whereby the pin may be pulled out of the aperture in said lug. Said head is provided with a laterally-projecting portion K² at right angles 60 thereto and is cut away at N and is adapted to turn in the angled or offset portion M' of the slot M, which is formed in said plate. Said portion K² is adapted to have a transverse movement in the elongated portion of 65 said slot M and prevents the pin coming out of the aperture in said lug by the end of said portion K² coming into contact with the end of said slot. When it is desired to remove the pin, it is pushed to its farthest 70 inward limit. Then a half-revolution is imparted to the pin sufficient to cause the portion K² to swing out of the offset portion of the slot and rest in a plane above the outer surface of the plate, after which the pin may 75 be readily removed, as will be understood. When the plate is swung closed, the locking-pin, it will be observed, is inserted through the registering apertures in said lug and in the integral apertured pin which projects 80 from the base of the buckle, and the plate is securely locked in a closed relation.

Having thus fully described my invention, what I claim as new, and desire to secure by Letters Patent, is—

1. In combination with a buckle, comprising a casing, an apertured lug projecting from the bottom thereof, a plate hinged to one of the longitudinal flanges of the buckle, a projecting portion on said plate which is 90 centrally apertured and adapted to receive said lug, a locking-pin adapted to pass through registering apertures in said projecting portion and lug, a portion of the head of said locking-pin designed to turn in the slot 95 in the plate to lock said pin in place, as set forth.

2. In combination with a buckle comprising a casing having flanged edges, an apertured lug projecting from said casing intermediate its flanges, a plate hinged to one of said flanges, and having a projecting portion

which is centrally apertured, a locking-pin adapted to be passed through transverse apertures in said projecting portion, a registering aperture in said projection, a head on said pin having a right-angled projecting portion K² which is adapted to turn in an offset portion of the slot in the plate, and having a transverse play in the elongated part of said

slot, said head being notched on one of its faces, as set forth.

In testimony whereof I affix my signature in presence of two witnesses.

FRANCIS E. RUSSELL.
